CLAIM

The ornamental design for a pipetting tip, as shown and described.

DESCRIPTION

FIG. 1 is a side perspective view of a pipetting tip according to a first embodiment of my new design;

FIG. 2 is a top and side perspective view thereof;

FIG. 3 is a bottom plan view thereof;

FIG. 4 is a top plan view thereof;

FIG. 5 is front elevation view thereof;

FIG. 6 is a rear elevation view thereof;

FIG. 7 is a left side elevation view thereof;

FIG. 8 is a right side elevation view thereof;

FIG. 9 is a side perspective view of a pipetting tip according to a second embodiment my new design;

FIG. 10 is a top and side perspective view thereof;

FIG. 11 is a bottom plan view thereof;

FIG. 12 is a top plan view thereof;

FIG. 13 is front elevation view thereof;

FIG. 14 is a rear elevation view thereof;

FIG. 15 is a left side elevation view thereof; and,

FIG. 16 is a right side elevation view thereof.
